VERTICAL LIFT CARGO PLANE

Norman E. Nelson, Palos Verdes Estates, Calif., assignor
to Doak Aircraft Co., Inc., Torrance, Calif., a cor-
poration of California

Filed Aug. 18, 1959, Ser. No. 57,220

Term of patent 14 years

(Cl. D71—1)

Fig. 5.

Fig. 1 is a top plan view of a vertical lift cargo plane of my new design;

Fig. 2 is a side elevational view thereof, the opposite side being substantially the same in appearance;

Fig. 3 is a front elevational view thereof;

Fig. 4 is a transverse section on the line IV—IV of Fig. 2; and

Fig. 5 is a perspective view of the bottom and side thereof.

I claim:

The ornamental design for a vertical lift cargo plane, as shown.
